UNITED STATES PATENT OFFICE.

ALBERT E. GRANT, OF NEW YORK, N. Y., ASSIGNOR TO CALOROIL BURNER CORPORATION, A CORPORATION OF DELAWARE.

APPARATUS FOR MIXING AND BURNING OIL.

Application filed February 21, 1920. Serial No. 360,516.

This invention relates to oil burners and particularly to a method and apparatus for providing a combustible mixture of oil and air. The chief object of the invention is to provide for the vaporization of the oil by highly heated gases such as steam with the admixture of air to form a composition burning with a hot flame of large volume and without the accumulation of a carbon deposit.

A further object of the invention is to provide simple and easily and safely operated apparatus for thus mixing the oil and air. In the accompanying drawings illustrating one embodiment of the invention in a burner

Fig. 1 is a diagrammatic elevation of the mixing and burning apparatus in connection with the flames to be heated by the burner,

Fig. 2 is a sectional elevation of a portion 20 of Fig. 1,

Fig. 3 is a horizontal section of the boiler and superheater,

Figs. 4 and 5 are respectively front and sectional views thereof and

Fig. 6 is an enlarged sectional elevation 25 of a portion of the mixing apparatus.

In the process of this invention a fluid such as water, preferably under substantially constant head is fed, for instance from 30 a tank 10 through pipe 11 to a cross pipe 12 which distributes it to the opposite ends 13 and 14 of a boiler and superheater 15 heated in any desirable manner. The water entering at 13 and 14 passes into the boiler 35 tubes 16 and 17 where it is vaporized and on into the tubes 18 and 19 where it is superheated and passed out at 20 through a pipe 21 connected to a steam jet supply 22 through a regulating needle valve 23 (see 40 Fig. 6) a funnel 30 being provided to carry away any water overflow.

The superheated steam is passed on through pipe section 24 to nozzle chamber 25 and out through nozzle 26 where it issues as 45 a jet forming around it a vacuum area at 27. In this vacuum area 27 is placed the upper end 28 of an oil supply tube 29 receiving oil from a substantially constant oil level supply means maintaining the level of the oil 50 in tube 29 considerably below the end 28 so that suction will be required to draw the oil up and out of the tube 29 and in the absence of such suction the oil level will recede below the outlet 28. Such oil supply means 55 may for instance be a barrel 35 connected

by siphon 36 to a tank 37 a small hand operated pump 38 and check valve 39 being provided to start the flow through the siphon. As the oil passes over through the pipe 36 it will fill the lower tank 37 and raise the 60 float 40 to close valve 41 and shut off the siphon supply and this flow and siphon will maintain constant level in the tank 37 so that the jet from the nozzle 26 will work against a substantially constant suction in 65 the oil pipe 29.

The jet of superheated steam issuing from nozzle 26 will thus draw up and vaporize a supply of oil from tube 29 and in the specific embodiment of the invention shown in the 70 drawings there will also be drawn in by the steam jet a supply of air through the pipe 42 the end 42' of which is also positioned in the vacuum space surrounding the jet. The mixed jet of steam, oil and air is then directed 75 through the nozzle 43 around which is a second or auxiliary steam nozzle 44 receiving its steam supply through the branch 45 from the supply 22. The nozzles 43 and 44 are preferably concentric and so arranged 80 that the auxiliary steam jet is in an annular sheet surrounding the central jet of steam, oil and air. This secondary jet further vaporizes the oil and mixes the steam, oil and air into a rapidly projected jet issuing 85 into the tube 50 of the burner which is preferably provided with air passages 51 and air holes 52 supplying further air to the final jet.

The jet issuing from the nozzles 43 and 44 90 is a highly inflammable and thorough mixture of steam, oil and air and will burn with a hot flame of large volume and without the deposit of any carbon or soot. In this specific embodiment of the invention shown in 95 Fig. 1 this flame from tube 50 is directed downward at an angle under the boiler and superheater 15 standing on legs 54 on a fire brick 55 which may for instance be placed over the grate 56 of the usual steam boiler 100 furnace. The flame curves upward around the tubes of the boiler and superheater 15 and extends upward to heat the tubes or water compartments of the boiler 56, the hot products of combustion finally passing 105 out through the usual chimney flue.

The control of the flame is exerted through 110 needle valve 23 of spindle 60 threaded through nut 61 and packed at 62 to be steam tight and carrying a hand wheel 63. The

greater the opening of the valve 23 the greater will be the pressure of the steam in nozzle 26 and the greater will be the vacuum in chamber 27 of the supply with a corresponding increase of oil and air. But in the specific embodiment of the invention shown auxiliary control of the air valve 65 is provided by linking this air valve with the spindle 60 as by sprockets 66 and 67 and the connecting chain 68 so that as the steam valve is opened, the cross section of the air throttle will also be increased to provide for a larger supply of air. The jet mixture through nozzle 43 is correspondingly increased as is also the steam jet through the surrounding nozzle 44 and more air is drawn in through the openings 51 giving a large volume with properly proportioned constituents. In the structure of the mixing apparatus shown in the drawings (see Fig. 6) all the parts are adjustable but predetermined in size and adjustment and the user is limited simply to the turning of the hand wheel 63. The parts of this mixer are easily constructed and assembled, cheapening the cost of production and making the structure convenient for repairs and replacements.

In the specific embodiment of the invention shown in the drawings the tank 10 for the water supply is preferably a constant level tank conveniently located in the building where the heater is installed. By feeding the water to the opposite ends 13 and 14 of the boiler and superheater two parallel passages for the steam are provided and connected at 65 so that fluctuations in pressure will be taken care of and equalized within the heater itself and without causing surging of the pressure and consequent inequalities in the flame. The boiler and superheater tubes 16, 17, 18 and 19 are preferably packed as indicated with small balls 70 of Monel metal which provide additional heating surface and act to restrict and make tortuous the passage through the tubes and also by their relative movement prevent the accumulation of scale. The boiler and superheater 15 is mounted on legs 54 not only to permit the free play of the flame from underneath but also to provide space for the removable priming pan 71 which is initially charged with oil and ignited to start the burner. This pan comprises a shallow metal container 72 filled with a porous pad 73 of asbestos or similar material and provided with a handle 74. To charge this pan with oil it must be removed from under the boiler 15 and pad 73 saturated with oil after which it is reinserted under the boiler and ignited and removed after the main burner begins to function. With this arrangement it is therefore impossible to pour the oil in fluid condition near the surfaces which are liable to be heated near the flash point of the oil and the priming charge of oil when inserted

under the boiler will necessarily be contained in the saturated pad 73 and so cannot cause an explosion.

The process of this invention not only mixes and remixes the steam, oil and air but also permits of easy control of the mixture by a single adjustment. The apparatus shown is simple in structure and efficient and safe in use. It is easily installed and after installation requires no attention except the necessary regulation of the size of the flame by turning of the single handle 63. The thorough vaporization of the oil and the thorough mixing of the superheated steam, air and oil produces a composition burning with an intensely hot flame of large volume which spreads over the relatively cool surfaces to be heated without the deposit of carbon. The apparatus utilizing this process is therefore clean and efficient and odorless in usefully consuming all of the fuel supplied.

I claim:

1. Apparatus for vaporizing and mixing oil comprising means adapted to form a steam jet and a valve adapted to control the steam jet, means adapted to supply oil to said steam jet, said oil supply being controlled by said steam jet, a valve adapted to simultaneously supply air to said oil supply steam jet, and a sprocket and chain connecting said steam valve and air valve whereby movement of the steam valve will control the steam, oil and air supplies.

2. Apparatus for vaporizing oil for a burner comprising means adapted to form a steam jet, a steam valve adapted to control said steam jet, means adapted to supply oil to said steam jet, an air valve geared to said steam valve to operate simultaneously therewith and adapted to supply air to said steam jet, and a second means adapted to form a second steam jet to combine with the mixture of oil, air and steam.

3. Apparatus for vaporizing oil for a burner comprising means adapted to form a steam jet, a steam valve adapted to control said steam jet, means adapted to supply oil to said steam jet, an air valve geared to said steam valve to operate simultaneously therewith and adapted to supply air to said steam jet, a second means adapted to form a second steam jet to combine with the mixture of oil, air and steam, and a second means adapted to supply air to the main mixture of oil, air and steam.

4. Apparatus for vaporizing oil for a burner comprising means adapted to form a steam jet, a steam valve adapted to control said steam jet, means adapted to supply oil to said steam jet, said oil being controlled by said steam jet, an air valve geared to said steam valve to operate simultaneously therewith and supply air to said steam jet, and a second means adapted to form a second surrounding annular jet of steam to

combine with the mixture of oil, air and steam controlled by said steam valve.

5. Apparatus for vaporizing oil for a burner comprising means adapted to form a steam jet, a valve adapted to control the steam jet, means adapted to supply oil to said steam jet, an air valve geared to said

steam valve to operate simultaneously therewith and adapted to supply air to said steam jet, and a second means adapted to supply air to the main mixture of oil, air and steam independent of the main mixture. ¹⁰

ALBERT E. GRANT.
